UNITED STATES PATENT OFFICE.

SAMUEL B. KIRKPATRICK, OF CHICAGO, ILLINOIS.

DISPLAY DEVICE.

Application filed February 18, 1925. Serial No. 10,087.

To all whom it may concern:

Be it known that I, SAMUEL B. KIRKPATRICK, a citizen of the United States, residing at Chicago, in the county of Cook 5 and State of Illinois, have invented new and useful Improvements in Display Devices, of which the following is a specification.

This invention relates to display devices especially adapted for use on motor vehicle 10 wheels, although not necessarily restricted to such use.

Briefly stated, an important object of this invention is to provide a display device in the nature of a hub cap having a name or 15 indicia bearing plate provided with a weighted portion by means of which the indicia or name on the plate is at all times held in an upright position so that the indicia or name may be readily read.

20 A further object of the invention is to provide a display device of the character specified which may be applied to a motor vehicle wheel without marring the appearance of the wheel or elaborately changing 25 the design of the wheel.

A further object is to provide a display device of the character specified which is of highly simplified construction, neat in appearance, and cheap to manufacture.

30 Other objects and advantages will be apparent during the course of the following description, and in the accompanying drawing forming a part of this application and in which like numerals are employed to designate like parts throughout the same.

35 Figure 1 is a front elevation of the improved display device applied.

Figure 2 is a vertical transverse sectional view through the improved display device 40 applied.

Figure 3 is a vertical sectional view taken on line 3—3 of Figure 2.

In the drawing, wherein for the purpose of illustration is shown a preferred embodiment of the invention, the numeral 5 designates the hub portion of a wheel of an automobile or the like. Figure 2 plainly illustrates that the hub 5 is exteriorly threaded for engagement with the hub cap 6, the said hub cap being provided at its upper end with an inwardly directed annular flange 7 which defines a centrally arranged sight opening 8. A plate 9 is positioned within the cap 6 and is provided with 55 a somewhat cylindrical projection 10 which may bear a name or any indicia. Figure 1

plainly illustrates that the indicia on the part 10 may be plainly seen through the sight opening 8 and as the rear side of the plate 9 is weighted as indicated at 11 the 60 name or indicia on the part 10 will at all times be in a horizontal position so that it may be easily read. The weighted part 11 is in the nature of a segment and is provided with a flange 12 arranged rearwardly 65 of and in line with the edge of the plate 9 so that the same may ride upon the anti-friction rollers 14 carried by the supports 16 and 18. The support 16 is in the nature of a disk, while the support 18 is in the 70 nature of an annulus, the center of which is in line with the center of the annular flange 7 to afford a full view of the matter or indicia on the projection 10. The supports 16 and 18 are held in spaced relation 75 by locking pins 20 of any desired type and to assure the best results the locking pins or connecting members 20 are longer than the anti-friction members 14 so as to prevent the ends of the anti-friction members 80 from binding against the inner surfaces of the members 16 and 18. Figure 3 plainly illustrates that the anti-friction members 14 and the connecting pins 20 alternate about the members 16 and 18 so that the members 85 16 and 18 are uniformly spaced.

Attention is directed to Figure 2 which illustrates that the thickness of the plate 9 and the weighted portion 11 is somewhat less than the space between the members 16 90 and 18 so that the plate 9 will not be likely to bind and turn with the hub cap.

In assembling the improved display device the members 16 and 18 are pressed lightly into the hub cap 6 to remain in place 95 and a proper lubricant is employed in the hub cap to reduce friction between the plate 9 and the anti-friction rollers 14 to a minimum.

It is believed to be obvious that the 100 weighted part 11 will hold the plate 9 against rotation during the turning of the wheel so that even when the vehicle to which the invention is applied is travelling the name or indicia on the part 10 may be easily 105 read. When the vehicle is brought to a halt all the plates 9 will occupy a predetermined position so that the name of the vehicle may be readily observed. Attention is directed to the fact that the projection 10 in the 110 opening 8 in the flange 7 will reduce the accumulation of mud, etc., to a minimum.

Having thus fully described my invention what is claimed is:-

1. A display device for wheels comprising a hub cap having a central opening, supports positioned within the hub cap and having anti-friction elements, and an indicia bearing plate positioned between said supports and being weighted whereby the indicia thereon will maintain a substantially fixed position.
2. A display device for hubs comprising a hub cap having a sight opening, supports within the hub cap, anti-friction elements carried by said supports, and a name bearing plate mounted on said anti-friction elements and visible through said sight opening, said plate being weighted whereby the indicia thereon remains in a predetermined position.
3. A display device for hubs comprising a hub cap having a sight opening, supports within the hub cap, anti-friction elements carried by said supports, and a name bearing plate mounted on said anti-friction elements and visible through said sight opening, said plate being weighted whereby the indicia thereon remains in a predetermined position, said plate being provided with an extension positioned within one of said supports.
4. A display device for hubs comprising a hub cap having a centrally arranged sight opening, supports within the hub cap, anti-friction elements carried by said supports, and connecting pins joining said supports.
5. A display device comprising a hub cap having an inwardly extending annular flange defining a sight opening, supports positioned within said cap rearwardly of said flange, anti-friction elements carried by said supports, a plate positioned between said supports and mounted on said anti-friction elements, said plate being weighted whereby the plate will ride on said anti-friction elements and remain in a predetermined position.
6. A display device comprising a hub cap having an inwardly extending annular flange defining a sight opening, a pair of spaced supports positioned within said cap rearwardly of said flange, anti-friction elements carried by said supports, a plate positioned between said supports and mounted on said anti-friction elements, said plate being weighted whereby the plate will ride on said anti-friction elements and remain in a predetermined position, said plate being provided with a cylindrical projection extending forwardly and adapted to bear indicia.

In testimony whereof I affix my signature.
SAMUEL B. KIRKPATRICK.
